COMBINED DESK AND TABLE

Mary Kathryn Cooper, Dayton, Ohio

Application February 20, 1943, Serial No. 476,547

7 Claims. (Cl. 311—101)

This invention relates to a combined desk and table and is designed more particularly for use in small apartments, hotel rooms and other places where furniture space is limited and it is desirable that one piece of furniture shall be adaptable for a plurality of uses.

One object of the invention is to provide a structure the several parts of which may be relatively adjusted to constitute either a desk or a table.

A further object of the invention is to provide such a structure which may be converted into any one of a plurality of tables of specifically different types.

A further object of the invention is to provide such a structure which will not only have a wide range of utility but will be of attractive appearance in each of the several forms to which it may be adjusted.

A further object of the invention is to provide such a structure which can be easily and quickly converted from one form to another form.

A further object of the invention is to provide such a structure which will comprise only a small number of relatively movable parts and which can be adjusted without the use of actuating devices or of supplemental supporting elements.

Other objects of the invention may appear as the device is described in detail.

In the accompanying drawing Fig. 1 is a perspective view of the adjustable structure in desk form; Fig. 2 is a perspective view of the structure with the parts adjusted to form one type of table; Fig. 3 is a perspective view of the structure with the parts adjusted to form a second type of table; Fig. 4 is a perspective view of the structure with the parts adjusted to form a console buffet; Fig. 5 is a plan view of the structure as shown in Fig. 1; Fig. 6 is a plan view of the structure as shown in Fig. 3; and Fig. 7 is a sectional detail view showing a portion of the bearing and guide.

The structure, or article of furniture, in its preferred form, comprises two pedestals 10 and a top which preferably consists of two parts or members 11 and 12 of equal size and superposed one upon the other. The two members of the top are relatively movable so that they may be either superposed one upon the other or placed edge to edge in a common plane, and are shown at 13 as hinged one to the other at their rear edges. The pedestals are shown as of the closed, drawer type as in the present instance it was desired to give the structure in its one form the appearance of a conventional "knee opening" desk. However, the pedestals may take any suit-

able form and may be of either the open or closed type. Preferably the pedestals are of a fore and aft length approximating the width of the top when the two members thereof are superposed one upon the other.

To form the desk the pedestals are moved to positions adjacent the respective ends of the two piece top, as shown in Fig. 1. It will be obvious of course that the pedestals may be provided 10 with any suitable number of drawers in any suitable arrangement or that other supporting devices or shelves may be substituted for the drawers. By moving the pedestals one toward the other into engaging or substantially abutting positions, as shown in Fig. 2, the two pedestals 15 constitute in effect a single pedestal and the top, with the two members thereof in superposed relation, projects lengthwise beyond the sides of the pedestals and thus forms a table at which two persons may be seated, there being knee room beneath each end of the table.

By moving the table top forwardly from the position shown in Fig. 2 for approximately half the width of one of the top members and then 20 moving the top member into the same plane with and into edge engagement with the bottom top member there is formed a table top as shown in Fig. 3, which projects on all four sides of the abutting pedestals and at which four or more 25 persons may be seated.

When the structure is in the position shown in Fig. 1 or Fig. 2 the upper member or leaf of the table may be moved to an upright position and supported in that position in any suitable 30 manner, as by placing the structure close to a wall. When the upper member of the desk top of Fig. 1 is moved to this position it forms a console buffet which can be utilized for many purposes. When the top member of the table of Fig. 2 is moved to an upright position the resulting structure is a console table or chest. The 35 conversion of the table of Fig. 2 into a console table is obvious and requires no illustration.

The pedestals may rest directly upon the floor 40 and the top may rest directly upon the tops of the pedestals. However, to facilitate the relative movement of the parts it is preferable that the pedestals be supported on casters of the semi-invisible type, and that anti-friction devices be 45 interposed between the top and the upper ends of the pedestals, together with means for guiding the relative movement of the pedestals and the top and of limiting those movements. The anti-friction and guiding devices may take various forms and may be arranged in various ways

and, as here shown, each pedestal is provided in its top, adjacent the respective corners thereof, with an anti-friction ball 14 seated in a metal socket 15 embedded in the top of the pedestal. The lower member 11 of the top should be provided with a metal facing 16 to engage the balls and the ball sockets 15 should be of such depth that the balls will extend only slightly above the surface of the pedestal so that the lower surface of the top will be close to the upper surfaces of the pedestals. The arrangement of the anti-friction balls is such as to prevent tilting of the top members. The guide means as here shown comprises two pins or studs 17 mounted in the tops of the respective pedestals and extending respectively into L-shaped guideways 18 formed in the lower surface of the top. In the arrangement shown the pins 17 are arranged adjacent the inner edges of the pedestals and when the latter are in their outermost positions as shown in Fig. 5 the studs will be at the outer end of the longitudinal portions of the L-shaped guideways. The movement of the pedestals to their innermost positions moves the studs 17 into the angular junction between the longitudinal and transverse portions of the respective guideways and thus releases the top for movement forwardly with relation to the pedestals, this forward movement bringing the rear ends of the transverse portions of the guideways into engagement with the pins, as shown in Fig. 6. It will be apparent that the guiding means constitutes a positive lock which prevents the transverse movement of the top when the pedestals are in their outer positions and prevents the movement of the pedestals to their outer positions after transverse movement has been imparted to the table top, and also that the engagement of the pins with the ends of the guideways positively limits the movement of the parts in the respective directions. It will be noted that the adjustment of the top with relation to the pedestals is effected while the upper member 12 is superposed on the lower member 11 and that after this adjustment has been completed the upper member is moved into the plane of the lower member and is supported on the bearing balls of the pedestals but it has no movement while in engagement with those balls.

While I have shown and described one embodiment of my invention I wish it to be understood that I do not desire to be limited to the details thereof as various modifications may occur to a person skilled in the art.

Having now fully described my invention, what I claim as new and desire to secure by Letters Patent is:

1. An article of furniture comprising a top, having upper and lower members supported one upon the other, and two pedestals having their upper ends in supporting engagement with the respective end portions of the lower member of said top, said pedestals being movable to positions adjacent the respective ends of said top or to substantially abutting positions spaced from said ends, said top being connected with said pedestals for sliding movement thereon transversely to the direction of movement of said pedestals to space the rear edge of the lower member of said top from the adjacent edges of said pedestals, and the upper member being pivotally connected with said lower member for movement into supporting engagement with the tops of said pedestals in the rear of said lower member to locate said members in the same horizontal plane.

2. An article of furniture comprising two pedestals, a top supported on said pedestals, said top and said pedestals being connected for movement with relation one to the other both lengthwise of and transversely to said top, anti-friction elements interposed between said top and the respective pedestals, and means to prevent the relative movement of said top and said pedestals in one direction until a predetermined relative movement thereof in another direction has been completed.

3. An article of furniture comprising two pedestals, a top supported on said pedestals, said top and said pedestals being connected for movement with relation one to the other both lengthwise of and transversely to said top, anti-friction elements interposed between said top and the respective pedestals, and means to prevent the transverse movement of said top with relation to said pedestals until said pedestals have been moved lengthwise of said top to substantially abutting positions midway between the ends of said top and to prevent the movement of said pedestals from said abutting positions after said top has been moved transversely and before it is returned to its initial position with relation to said pedestals.

4. An article of furniture comprising a top having upper and lower members supported one upon the other and two pedestals having their upper ends in supporting engagement with the respective end portions of the lower member of said top, said pedestals being movable to positions adjacent the respective ends of said top and to substantially abutting positions spaced from said ends, said top being connected with said pedestals for movement transversely to the direction of movement of said pedestals to space the rear edge of the lower member of said top from the adjacent edges of said pedestals and the upper member being pivotally connected with said lower member for movement into supporting engagement with the tops of said pedestals in the rear of said lower member to locate said members in the same horizontal plane, each pedestal including a plurality of anti-friction elements having supporting engagement with said top, the anti-friction elements of each pedestal being so arranged that when said upper member is supported on said lower member all of said elements will engage said lower member and when said top has been moved transversely with relation to said pedestal and the two members thereof are in the same plane a part of said anti-friction elements will engage said lower member and another part thereof will engage said upper member, thereby preventing the tilting of said top in all operative positions.

5. An article of furniture comprising a top, having upper and lower members supported one upon the other, and two pedestals having their upper ends in supporting engagement with the respective end portions of the lower member of said top, said pedestals being movable to positions adjacent the respective ends of said top or to substantially abutting positions spaced from said ends, said top being movable on said pedestals transversely to the direction of movement of said pedestals to space the rear edge of the lower member of said top from the adjacent edges of said pedestals, and the upper member being movable with relation to said lower member into supporting engagement with the tops of said pedestals in the rear of said lower member to locate said members in the same horizontal

plane, said pedestals and said top having inter-engaging parts to control the direction of the relative movements thereof and to limit such movements.

6. An article of furniture comprising a top having upper and lower members supported one upon the other, and two pedestals having their upper ends in supporting engagement with the respective end portions of the lower member of said top, said pedestals being movable to positions adjacent the respective ends of said top or to substantially abutting positions spaced from said ends, said top being movable on said pedestals transversely to the direction of movement of said pedestals to space the rear edge of the lower member of said top from the adjacent edges of said pedestals, and the upper member being pivotally connected with said lower member for movement into supporting engagement with the tops of said pedestals in the rear of said lower member to locate said members in the same horizontal plane, said top and said pedestals having cooperating parts to prevent the transverse movement of said top while said pedestals are positioned adjacent the ends of said top.

7. An article of furniture comprising a top having upper and lower members supported one upon the other, and two pedestals having their upper ends in supporting engagement with the 5 respective end portions of the lower member of said top, said pedestals being movable to positions adjacent the respective ends of said top or to substantially abutting positions spaced from said ends, said top being movable on said pedestals 10 transversely to the direction of movement of said pedestals to space the rear edge of the lower member of said top from the adjacent edges of said pedestals, and the upper member being movable with relation to said lower member into 15 supporting engagement with the tops of said pedestals in the rear of said lower member to locate said members in the same horizontal plane, the lower member of said top being provided with two right angle grooves having aligned portions 20 extending lengthwise of said top and parallel portions extending transversely thereto and pins carried by said pedestals and extending into the respective grooves.
